UNITED STATES PATENT OFFICE

2,037,803

EXPLOSIONPROOF TELEPHONE

Ray F. Lester, Syracuse, N. Y., assignor to Crouse-Hinds Company, Syracuse, N. Y., a corporation of New York

Application June 28, 1935, Serial No. 28,900

9 Claims. (Cl. 179—100)

This invention has for its object, an entirely closed, explosion proof box for housing a dial telephone mechanism, and particularly a construction whereby the dial mechanism is operable from an extension dial on the outside of the box, and the receiver, or the combined receiver and microphone or transmitter, carried by an extension cradle, or rest, on the outside of the closed box.

It further has for its object, an arrangement of the motion transmitting means between the extension dial and the extension receiver, and the dial and switch of the telephone mechanism respectively, whereby outlet passages with large surface areas are provided to retard and cool the outlet of heated exploded gases from the interior of the box so that the gases are cooled below the ignition point of volatile vapors that may be in the surrounding atmosphere.

Other objects will appear throughout the specification.

In general, the box is intended for use in situations where there are volatile explosive gases in the surrounding atmosphere, such as in mines, oil fields, distillation plants, gas houses, gasoline stations, etc. It will be understood that in such situations, ignitable gases and vapors within the box are liable to be ignited by sparks occurring during the operation of switches and the like within the telephone mechanism, operable during the dialing, or during the opening of the switch, and operable by the removal of the receiver from its rest. Explosions caused by sparking are, by this invention, confined within the box, and the escaping gases cooled before they find their way to the surrounding atmosphere.

The invention consists in the novel features and in the combinations and constructions hereinafter set forth and claimed.

In describing this invention, reference is had to the accompanying drawings in which like characters designate corresponding parts in all the views.

Figure 1 is a front elevation of this box and contiguous parts of the telephone apparatus.

Figure 2 is a vertical, sectional view on Figure 1.

This box comprises a body 1, and cover 2, the body being of impervious, non-combustible material and strong enough to withstand explosions. They are usually castings.

3 designates, generally, the telephone mechanism; 4 the dial thereof, and 5 the bell switch which is normally closed and held closed by the receiver, or the combined receiver and micro-

phone, or transmitter, and opened by the lifting of the receiver from its rest, or cradle.

The dial is of the usual rotary type, rotatable from a starting or zero position through various radial angles depending on which of the holes of the dial the finger is inserted into for turning the dial until limited by a finger stop.

The movable door 2 closes an opening in one wall of the body of the box, through which the telephone mechanism is removable and replaceable when the door is removed or opened. This door is here shown as circular, and as screw threaded into an annular flange 8 on the front face of the box.

9 is an extension dial which is practically a duplicate of the dial 3 and operable through the same angles as the dial 4, it being limited in its movement by a stop 10 fixed to the door 2. Suitable motion transmitting means is provided between the extension dial 9 and the dial 4, the extension dial being here shown, and preferably, carried by the door and including a coupling which uncouples from the dial 4 when the door is removed, or opened, and couples therewith when the door is replaced, or closed. The motion transmitting means is here shown as a shaft 11 journalled in the door 2 coaxially therewith, and also coaxially with the dial 3, the extension dial 9 being mounted on the outer end of the shaft 11, and the coupling including a crank arm 12 on the inner end of the shaft 11 and having a crank pin which fits into one of the holes of the telephone dial 3, usually the zero hole, or the hole nearest the stop corresponding to the stop 10. The shaft 11 is here shown as journalled in a bushing 13 mounted in the door 2, and the door is cup-shaped, and the bushing mounted in an elongated hub or bearing located on the inner side of the door and terminating near the dial 4 in order to provide a long bearing for the rock shaft 11. The purpose of the long bearing and shaft is to provide surfaces of large area with which any heated gases must come in contact in finding their way out along the shaft 11, these large surfaces baffling, or retarding, and cooling the gases during their passage outward, to a point below the ignition point of any volatile vapors in the surrounding atmosphere.

Likewise, the threaded contact between the door 2 and the flange 8 provides retarding and cooling surfaces of sufficient area to cool the heated gases below their ignition point before they find their way to the outer atmosphere.

The dial 9 is mounted on a reduced, flattened end 14 of the shaft 11 and abuts against a shoulder

at 15 thereon. It is held in position by a cap nut 16. The dial 9 is thus keyed to the shaft 11 to transmit a rotary movement thereto. The reduced end is oblong and extends diametrically 5 of the outer end of the shaft 11, the end of the oblong being threaded to receive the threads of the nut. The dial 9 has a complementary oblong slot to receive the reduced end.

Means are provided for locating the door 2 10 when it is screwed into the body to such position that the finger stop 10 is located in juxtaposition to the zero position of the dial 4 of the telephone mechanism, this means being here 15 shown as a set screw 17 threading through a flange on the periphery of the cover and coacting with a spot, or depression, 18 in the edge of the flange 8.

In operation, the door 2 is screwed into the flange 8, and the shaft 11 being rotatably mounted 20 therein does not turn, but is allowed to hang vertically downwardly and therefore, passes into the zero hole 20 of the inner dial 4. Then, in order 25 to locate the finger stop 10, which is carried by the door, the door is turned, when in nearly its final position, until the set screw 17 is in line with the spot 18, and the set screw 17 tightened.

The extension means for operating the switch 5, as here shown, includes an axially movable rod 25 slideable in an extension bushing 26 threading 30 into the top wall of the box, the rod having a foot 27 at its lower end coacting with the operating member 28 of the switch 5 and carrying, at its upper end above the bushing, a head 29 for coacting 35 with the combined receiver and microphone or transmitter 30 when on its rest. The weight of the receiver and microphone unit causes the rod 25 to move downwardly and close the switch 5. The movement downwardly is against the action 40 of a suitable returning spring 31 located in a counterbore 32 in the upper end of the bushing 26, the spring encircling the rod and abutting at one 45 end against the bottom of the recess, and at its other end against the head 29 at the upper end of the rod 25. The head 29 is secured to the rod by a screw 33. The intermediate part, or yoke, of the 50 receiver or microphone unit presses on the head 29 and holds the rod depressed and the switch 5 closed. The bushing carries a cradle 34 for the receiver and microphone unit, the bushing and the cradle constituting an extension rest for the 55 unit. The sliding surface contact between the rod 25 and the bushing is of sufficient extent to provide surfaces of large enough area to retard and cool the gases during the passage of the heated gases out along the rod 25. The rod 25 is held from undue upward movement by the spring, when the receiver is removed, by a stop washer 36 located in a groove 37 in the lower end portion 60 of the rod 25 in position to abut against the lower end of the bushing 25 when the receiver is removed.

The body of the box is also provided with bosses 40 which may be threaded to receive a conduit line enclosing the surface wires, and is also provided with a connector 41 to receive the cord 42 which 65 connects the telephone apparatus within the box with the receiver and transmitter. The box is also formed with suitable means as lugs 38 by which it can be secured to a wall, post, or other support.

What I claim is:

70 1. A box for completely enclosing a dial telephone mechanism which includes a manually operable dial and a switch having a movable member operable by the removal of the receiver from its rest, said box comprising a body and a movable door through which the telephone mecha-

nism is removable and replaceable, an extension dial carried by the door on the outer side thereof, motion transmitting means between the latter dial and the dial of the telephone mechanism within the box, a receiver rest on the outside of the box, and motion transmitting means between the receiver on said rest and the movable member of the switch, whereby the switch is operated by the removal of the receiver from, and replacement on its rest. 10

2. A box for completely housing a dial telephone mechanism which includes a manually operable dial and a switch having a movable member operable by the removal of the transmitter, said box comprising a body and a movable door 15 through which the telephone mechanism is removable and replaceable, an extension dial carried by the door on the outer side thereof, motion transmitting means between the latter dial and the dial of the telephone mechanism within the box, a receiver rest on the outside of the box, and motion transmitting means between the receiver on the rest and the movable member of the switch, whereby the switch is operated by the removal of the receiver from, and replacement on 20 its rest, the door and the box having passages for said motion transmitting means in which said means slidably fit. 25

3. A box for completely housing a dial telephone mechanism which includes a manually operable dial and a switch having a movable member operable by the removal of the receiver from its rest, said box comprising a body and a movable door through which the telephone mechanism is removable and replaceable, an extension dial carried by the door on the outer side thereof, motion transmitting means between the latter dial and the dial of the telephone mechanism within the box, a receiver rest on the outside of the box, and motion transmitting means 30 between the receiver on the rest and the movable member of the switch, whereby the switch is operated by the removal from, and replacement of the receiver on its rest, the door and the box body having passages for said motion transmitting means, the motion transmitting means and the walls of the passages being formed to provide surfaces of sufficient area to retard and cool the outlet of heated exploded gases from the box. 35

4. A box for completely enclosing a dial telephone mechanism which includes a manually operable dial, and a switch having a movable member operable by the removal of the telephone receiver from its rest, a dial carried on the outer side of the box, motion transmitting means between the latter dial and the dial of the telephone mechanism, an extension receiver rest on the outside of the box, and motion transmitting means between the receiver on the rest and the movable member of the switch. 50

5. A box for completely enclosing a dial telephone mechanism which includes a manually operable dial and a switch having a movable member operable by the removal and replacement of the telephone receiver from and on its rest, a dial 65 carried on the outer side of the box, motion transmitting means between the latter dial and the dial of the telephone mechanism, and an extension receiver rest on the outside of the box, and motion transmitting means between the rest and the 70 movable member of the switch, the box being provided with elongated passages in which said motion transmitting means slidably fit providing surfaces of sufficiently large area to retard and cool the outlet of heated exploded gases from the box. 75

6. A box for completely enclosing a dial telephone mechanism which includes a manually operable dial, and a switch having a movable member operable by the removal and replacement of the telephone received from and on its rest, said box having a door through which the telephone mechanism is removable and replaceable, the door being coaxial with the dial and removable and replaceable by a rotary and axial movement, 5
10 a rock shaft journalled in the door coaxially therewith and coaxially with the dial, an extension dial mounted on the shaft on the outside of the door, a coupling at the inner end of the shaft and coacting with the dial of the telephone mechanism to transfer the rotary movement of the shaft to the dial of the telephone mechanism, said coupling coacting with the dial of the telephone mechanism to uncouple therefrom and couple therewith upon opening and closing of the door, the door having a hub on its inner side terminating near the dial of the telephone mechanism in which the rock shaft is 15 journalled providing a long passage for the outlet of exploded gases, an extension receiver rest on the outside of the box, and means housed in the rest for operating the switch of the telephone mechanism when the receiver is removed from and replaced on the extension rest. 20

7. A box for housing a dial telephone mechanism which includes a manually operable dial, and a telephone switch having a movable member operable by the removal and replacement of the telephone receiver from and on its rest, said box having a movable door through which the telephone mechanism is removable and replaceable, a rock shaft journalled in the door coaxially with the dial, an extension dial mounted on the shaft on the outside of the door, a coupling at the inner end of the shaft and coacting with the dial of the telephone mechanism to transfer the rotary movement of the shaft to the dial of the telephone mechanism, said coupling coacting with the dial of the telephone mechanism to uncouple therefrom and couple therewith upon opening and closing movements of the door, an extension receiver rest on the outside of the box, and means housed in the rest for operating the switch of the telephone mechanism when the receiver is removed from and replaced on the extension rest. 35

8. A box for housing a dial telephone mechanism which includes a manually operable dial, and a telephone switch having a movable member operable by the removal and replacement of

the telephone receiver from its rest, said box having a movable door through which the telephone mechanism is removable and replaceable, a rock shaft journalled in the door coaxially with the dial, an extension dial mounted on the shaft on the outside of the door, a coupling at the inner end of the shaft and coacting with the dial of the telephone mechanism to transfer the rotary movement of the shaft to the dial of the telephone mechanism, said coupling coacting with the dial of the telephone mechanism to uncouple therefrom and couple therewith upon opening and closing of the door, the door having a hub on its inner side terminating near the dial of the telephone mechanism in which the rock shaft is 15 journalled providing a long passage for the outlet of exploded gases, an extension receiver rest on the outside of the box, and means housed in the rest for operating the switch of the telephone mechanism when the receiver is removed from 20 and replaced on the extension rest.

9. A box for housing a dial telephone mechanism which includes a manually operable dial, and a telephone switch having a movable member operable by the removal and replacement of the telephone receiver from and to its rest, said box having a movable door through which the telephone mechanism is removable and replaceable, the door threading into the box and arranged coaxial with the dial of the telephone mechanism, a shaft journalled in the cover coaxial therewith and having a coupling at its inner end coacting with the dial of the telephone mechanism, and an extension dial mounted on the outer end of the shaft, a finger stop carried by the door for limiting the movement of the extension dial at a predetermined point, and means for locating the door in its final position with said stop in a predetermined position, an extension receiver rest on the outside of the box including a bushing extending into the box, a rod slidably fitting the bushing and coacting at its inner end with the movable switch member and having its outer end arranged to be engaged and moved inward by the receiver when on the rest. 35 40 45

RAY F. LESTER.
